METHOD OF MAKING A CONTAINER

Herman Carew, Easton, Pa., assignor to Dixie-Vortex Company, Chicago, Ill., a corporation of Delaware

Application October 28, 1938, Serial No. 237,432

5 Claims. (Cl. 93—36.2)

This invention relates to improvements in a container and method of making the same, and more particularly to a container of the type of a paper drinking cup, ice cream cup, or similar paper or fiber container of the character customarily discarded after a single usage, although the invention may have other uses and purposes as will be apparent to one skilled in the art.

An important object of this invention is the provision of a paper cup, of the character of a drinking cup, an ice cream cup, etc., bearing a printed pattern or other form of printing for identification, decoration and similar purposes.

Another important object of this invention is the provision of a new and novel method of making or producing the aforesaid cup or container.

In the past, extreme difficulty has been experienced in manufacturing paper cups, containers and the like, with printed material appearing on the finished product. This difficulty was increased when devices of the character of drinking or ice cream cups were manufactured from blanks of stock. The difficulty was still further and very greatly increased in the manufacture of a conical paper cup from a single, substantially sector-shaped blank of stock.

Heretofore, various methods of producing printed matter upon a paper cup have been used. One of these methods was to provide spaced patches of printing upon a ribbon of stock and sever the blanks from the ribbon with each blank including a patch of printing. However, it was very costly to maintain the proper alignment of the stock ribbon, so that each blank would be cut and carry a patch of printing in the same location as every other blank, and so that all finished containers would be uniform in appearance. If, for any reason, the stock ribbon became out of line or was not started through the machine at the exact point, even for a small distance of one-eighth of an inch, the resultant containers would not be uniform in appearance with other containers. To maintain such a high degree of accuracy in the feeding of the stock ribbon and the cutting of the blanks was objectionably expensive.

In the manufacture of paper cups, such as drinking and ice cream cups, which for sanitary reasons are discarded after a single usage, economy in production is an essential. While the particular economy involved may not be so apparent from a single blank or a single cup, that economy is very greatly apparent when considered with the production cost of millions of cups. Therefore, to materially reduce the cost in the

production of cups carrying printed matter thereon is a highly important advance in this art.

With the foregoing in mind, it is a further object of this invention to provide a method of producing printed container blanks, wherein the printing is applied to a stock ribbon in such a manner that blanks may be severed from the stock ribbon at any location therealong and be uniform in appearance with blanks severed from the stock ribbon at other locations therealong.

In manufacturing paper cups or containers in which the finished container has overlapped marginal portions of the blank, it is quite important that no printing appear on the inner of the overlapped marginal portions so as to be partially visible through the outer of the overlapped portions and thus mar the appearance of the cup or container as a whole.

Accordingly, another object of this invention is the provision of a method of making a printed cup or container blank, wherein printing is applied initially to a stock ribbon, and blanks are successively severed from substantially any location along the stock ribbon with each severed blank being so positioned that the printing will not appear on the inner of the resultant overlapped portions of the blank.

Another object of the invention resides in the provision of a new and novel method of producing a container blank having a substantially continuous line of printing running thereacross, which line of printing may, if so desired, be substantially straight in character, regardless of whether or not the blank is to be formed into a conical container by shaping it convolutely or otherwise.

It is also an object of the invention to provide a method of making printed paper container blanks, wherein a continuous line of printing is provided along a stock ribbon, and blanks are successively severed from the stock ribbon through said line of printing.

A further and more specific object of the invention is the provision of a method of producing substantially sector-shaped blanks of stock, each of which is to be formed into a conical container, and each of which contains printed matter extending thereacross and which will be completely visible on the exterior surface of the finished container.

Still another feature of the invention is the provision of a method of producing printed container blanks, wherein the printing is applied to a ribbon of stock, and the blanks may be severed from such ribbon in a known or usual manner.

without any increase of waste stock, and with each blank carrying printed matter similar to every other blank and with the printing so located that all containers will be equally uniform 5 and as pleasing in appearance.

Another feature of the novel method embodied in this invention resides in the fact that the practice of the method produces a container blank carrying printed matter, but requires no 10 alterations or additions to blank cutting mechanism now in use.

A further important feature of the present novel method resides in the fact that the method may be used equally as well in the making of 15 blanks which are pre-cut, stacked and then fed one at a time from the stack to forming mechanism, or in machines wherein a ribbon of stock is fed through the machine towards the forming mechanism, and each blank is formed as it is 20 severed from the stock ribbon.

Still another object of the invention is the provision of a novel printed container.

While some of the more salient features, characteristics and advantages of the present invention have been above pointed out, others will become apparent from the following disclosures, taken in conjunction with the accompanying drawings, in which:

Figure 1 is a plan view of a printed container blank embodying principles of the present invention and manufactured by virtue of the novel method embodied in this invention;

Figure 2 is a side elevational view of a container made from the blank of Figure 1;

Figure 3 is a side elevational view of the container of Figure 2, taken from a different position;

Figure 4 is a somewhat diagrammatic view in plan, illustrating the practice of the present invention to produce a blank of the character of that shown in Figure 1;

Figure 5 is a side elevational diagrammatic view of the practice of the novel method here involved, illustrating diagrammatically certain apparatus which may be used;

Figure 6 is a diagrammatic view in plan similar in character to Figure 4, illustrating the practice of the present method, wherein the blanks are not pre-cut, stacked, and assembled prior to 50 each blank being formed into container shape;

Figure 7 is a side elevational view of a container made from one of the blanks shown in Figure 6; and

Figure 8 is another side elevational view of the container of Figure 7, taken from a different angle.

As shown on the drawings:

With reference to Figures 1, 2 and 3, it will be seen that one of the illustrated embodiments of 60 the present invention includes a substantially sector-shaped blank 10 of suitable material, such as paper commonly used for the making of paper drinking cups, ice cream cups, and the like, either of the so-called dry wax type or the wet wax type. This blank is designed to form a conical cup 10a as seen in Figures 2 and 3.

The blank includes a relatively large arcuate edge 11 to define the mouth of the resultant cup and a pair of converging side edges, which for 70 the purpose of description may be termed substantially radial edges, 12 and 13. These edges do not meet but are connected by means of an extension tab 14. The edge 12, which will be the outside edge of the finished container, is 75 substantially straight, while the resultant inner

edge 13 is preferably curved to facilitate forming of the container. The extension tab 14 is wound around the apex of the finished container, as seen clearly in Figures 2 and 3.

The blank 10 is provided with a substantially 5 continuous line of printing 15 extending completely across the blank. In this instance, the term "line" is used to designate any elongated patch of printing of substantially any character, whether or not it is strictly a line or a design 10 having non-uniform edges as illustrated. While the specific contour of the printing 15 may vary somewhat, it is preferable to have the line generally straight across the blank, since a substantially straight running printed pattern is easier 15 to apply.

It will be noted that the printing runs from an intermediate point on the straight edge 12 to an intermediate point on the arcuate edge 11, missing entirely the ultimate inner curved edge 20 13. With this disposition of the printed matter 15, the line of printing is caused to curve around the finished container and substantially circumscribe the container, as seen in Figures 2 and 3, 25 all of the printed matter appearing on the outside surface of the container. The two ends of the line of printing terminate substantially in the same plane, although they are spaced apart, as clearly seen in Figure 3. Of course, other judicious locations for the printed matter upon 30 the blank may be determined, depending upon the character of the printing and the desired resultant location on the container. By avoiding any printing along the margin of the edge 13, the printed matter is entirely on the outside 35 surface of the container, with no printed matter on the inner of the overlapped marginal portions which would be partially visible through the outer margin and thus spoil the nice appearance of the container. When the blank 10 is wound 40 convolutely into a cup 10a of Figures 2 and 3, the printed matter is also disposed around the container in substantially convolute fashion, in keeping with the formation of the container. Of course, it will be appreciated that several lines 45 of printing may be provided, if so desired, the illustrated printing being by way of example and not by way of limitation.

In Figures 4 and 5, I have diagrammatically 50 illustrated a novel method of producing finished blanks. For pre-cut blanks, such as are initially cut, stacked, and then fed one at a time to forming mechanism, it is more economical to provide a stock ribbon from which a plurality of rows 55 of blanks may be severed. By properly arranging the cutting dies, stock waste is reduced to a minimum.

In this instance, I have illustrated a stock ribbon 16 of proper width for the severing therefrom of two rows of blanks, the blanks in one 60 row being disposed oppositely to the blanks in the other row. Prior to the severance of any blank, two continuous lines of printing 15a are provided upon the stock strip 16. These lines are also opposite in character in keeping with the 65 rows of blanks to be cut from the strip. It is a simple matter to print a stock strip with two continuous lines of printing, such as the lines 15a. This may be accomplished by mechanism illustrated diagrammatically in Figure 5. The 70 stock strip may be wound at proper speed from a supply roll 17 and fed between a printing roll 18 and a backing roll 19, the printing roll supplying both of the lines of printing to the stock ribbon. The ribbon next proceeds into a suit- 75

able punch and die cutting mechanism 20, preferably arranged to simultaneously punch two or more blanks from the stock ribbon.

At this point, it may be best to mention that 5 where the term "continuous" is used herein and in the appended claims, this term is to be construed as including substantially any type of elongated printed pattern, interrupted or uninterrupted, and preferably of such a character 10 that the line can be cut through anywhere therealong without causing any appreciable change in the printing upon one finished container as compared with that upon another finished container.

By this method of providing printed blanks, it 15 will be noted that a line of printing may be so located as to be immediately adjacent or in proximity to the narrowest waste space between succeeding blanks. It will further be noted that no particular alignment or timing of the stock 20 ribbon is necessary, since a blank may be punched from substantially any location along the stock ribbon and through the respective line of printing, and the container made from this blank will appear exactly similar to containers made 25 from blanks cut from other locations along the stock ribbon. Further, the method is extremely economical and necessitates no change whatsoever in cutting mechanism of the type used to provide unprinted blanks. It will be understood, 30 of course, that the printed pattern may be located in various positions transversely of the blank, it being preferable to avoid the provision of printing running to the resultant inner edges 18 of the blank for the reasons above explained.

35 In order to definitely illustrate that the present method of providing printed blanks is not limited to the provision of pre-cut blanks or to the provision of blanks which are ultimately convolutedly wound to form containers, I have illustrated in Figures 6, 7 and 8 the application of 40 the method to a stock strip for use in the so-called ribbon feed machine. In such machines, a stock ribbon is fed continuously entirely through the machine, the blanks being severed successively 45 in a single row, and each blank is formed into a container immediately after its severance from the leading end of the stock ribbon. The blanks and cups shown in these figures are of the type more fully disclosed, described and claimed in 50 my copending application for Letters Patent entitled "Container and blank therefor," filed September 9, 1937, Serial No. 162,968.

In this instance, a stock ribbon 21 of proper width for the cutting of a single row of blanks is provided in the manner above explained or 55 in an equivalent manner, with a substantially continuous line of printing 22. Blanks 23 are successively severed from the leading portion of the strip and immediately after severance are 60 respectively formed into containers. These blanks are substantially sector-shaped and each includes an arcuate edge 24 to define the mouth of the resultant cup, and a pair of converging side edges 25 and 26. As previously explained, it 65 is preferable to have the printing 22 entirely miss one of the converging side edges which will be the inner of the overlapped edges in the finished cup. In this instance the edge 25 and the adjacent margin is free from printing.

70 The blank is formed into a cup by merely overlapping the margins adjacent the edges 25 and 26 in a substantially straight side seam 27, as seen in Figure 7. Even with such formation, the printing 22 assumes a somewhat convolute line around the cup, and if the printing is lo-

cated substantially centrally of the blank, the printing will substantially circumscribe the cup.

Since the upper face of each severed blank is 5 the inside surface of the finished cup, it is necessary in this instance to provide the printing on the underside of the stock ribbon. This can be done very easily by proper disposition of the printing mechanism or by unwinding the stock supply roll, applying the printing, and rewinding the roll in reverse order.

10 It will, of course, be appreciated that blanks may be provided by the method embodied in this invention by cutting the blanks from a stock ribbon, a strip or sheet, and to such extent the terms "ribbon," "strip," and "sheet" are 15 used synonymously herein and in the appended claims. Accuracy and economy of manufacture are efficiently provided both when blanks are successively severed from a strip or ribbon and where a sheet or stack of sheets is placed under 20 a multiple die for cutting some or all of the blank capacity of a sheet at a single operation.

25 From the foregoing, it is apparent that I have provided a novel method of producing a printed cup blank and container, the method and container both being substantially as economical as though no printing had been provided, the only additional expense being the very nominal cost of applying the printing to the stock ribbon. In view of the fact that the containers may 30 be severed from substantially any location along the stock ribbon and all resultant cups are quite similar in appearance, the method is very feasible and may be practiced economically and with great 35 facility.

I am aware that many changes may be made and numerous details of construction may be varied through a wide range without departing from the principles of this invention, and I, therefore, do not purpose limiting the patent 40 granted hereon otherwise than is necessitated by the prior art.

45 I claim as my invention:

1. The method of producing a printed paper cup blank, including the steps of running a continuous line of printing along a stock strip, and then severing substantially sector-shaped blanks from said strip, each blank being cut to include a part of said line of printing and in such position that a substantially radial edge 50 thereof is disposed completely to one side of said line of printing.

2. The method of producing printed blanks each to be formed into a cup with portions of the blank overlapped, including the steps of running a continuous line of printing along a stock ribbon, and successively cutting blanks from said ribbon through said line of printing with each blank disposed so that no printing will appear 55 on the inner of the resulting overlapped portions.

3. The method of producing printed blanks each having a pair of marginal portions overlapping when the blank is subsequently formed into a container, including the steps of running a continuous line of printing along a stock ribbon, and successively cutting blanks from said ribbon through said line of printing with the blank 60 so disposed that the line of printing extends across the blank between the edge of the outer of the resultant overlapped margins and a point 65 remote from the inner of the resultant overlapped margins.

4. In a method of making blanks for paper containers wherein substantially sector-shaped blanks each having an arcuate edge joining con- 70

verging side edges are struck from a stock ribbon having a line of printing running therealong, the step of severing each blank from the ribbon in such location that the line will cross the
5 blank but leave free of printing that part of the margin adjacent one side edge which becomes the inner portion of the overlapped seam when the container is formed from the blank.

5. The method of making a conical paper cup,
10 including the steps of running a continuous line

of printing along a stock ribbon, severing a cup blank from said ribbon through said line of printing in such location that one side margin of the blank is devoid of printing, and then forming said blank convolutely into conical shape 5 with overlapped marginal portions of which said one side margin is the inner, and with the line of printing appearing substantially convolutely and wholly on the outer surface of the cup.

HERMAN CAREW. 10
